UNITED STATES PATENT OFFICE.

CARL J. E. WAXBOM, OF COLUMBUS, OHIO, ASSIGNOR TO THE JEFFREY MANUFACTURING COMPANY, OF COLUMBUS, OHIO, A CORPORATION OF OHIO.

MINING-MACHINE.

1,212,717.

Specification of Letters Patent. Patented Jan. 16, 1917.

Application filed September 18, 1913. Serial No. 790,442.

To all whom it may concern:

Be it known that I, CARL J. E. WAXBOM, a citizen of the United States, residing at Columbus, in the county of Franklin and State of Ohio, have invented certain new and useful Improvements in Mining-Machines, of which the following is a specification, reference being had therein to the accompanying drawing.

10 This invention relates more especially to side cutting mining machines which are adapted for use in "room and pillar" mining. Machines of this character, as now commonly constructed and used, comprise a bed frame, an endless chain cutter frame projecting from the inner end of the bed frame, a power-actuated flexible draft device—cable, chain or the like—arranged to exert a forward draft on the inner end of the bed frame to propel the machine along the face of the coal, and a further flexible draft device arranged to exert a retarding draft on the outer end of the bed frame to counteract the reaction of the coal on the cutter frame which, when the machine is fed forward along the face of the coal, tends to cause the outer end of the machine to swing or slew around in advance of the other parts. By providing a suitable retarding draft on the outer end of the machine the latter can be guided and controlled in its movements as desired.

20

25

30

One of the objects of my invention is the provision of a machine of the character referred to having a power actuated propelling cable or the like and a retarding cable which is paid out as the machine advances at a rate independent of the power driven propelling devices, but, at the same time, is capable of having power applied to it for the purpose of positively swinging the outer end of the machine rearward so as to vary its working angle to the coal face.

Another object of the invention is the provision of a retarding cable, such as last mentioned, in combination with suitable guide devices on the bed frame over which the retarding cable can be passed and carried to a distant anchor or the like so that when power is applied to the cable, it serves to move the machine toward the fixed anchor or abutment.

The above, and other more or less incidental or ancillary objects of my invention, and the manner of attaining them, will be clearly

understood from the following description and claims taken in connection with the accompanying drawings in which I illustrate a preferred embodiment of the invention.

Figure 1 is a plan view of the machine, a part of the cutter being broken away. Fig. 2 is a left side elevation of the same. Fig. 3 is a transverse section on the line 3—3 of Fig. 1, the cutter chain being omitted. Fig. 4 is a vertical transverse section on the line 4—4 of Fig. 1. Fig. 5 is a detail vertical sectional view of the clutch which connects the driving gearing to the rear sprocket wheel of the cutting chain, and of the devices for actuating said clutch. Fig. 5^a is a face view of the said clutch actuating device. Fig. 6 is a plan view on a larger scale of the inner part of the bed frame and of the gearing with gear casing removed. Fig. 7 is a vertical longitudinal section on the line 7—7 of Fig. 6. Fig. 8 is a vertical section on the line 8—8 of Fig. 6. Fig. 9 is a vertical transverse section on the line 9—9 of Fig. 6. Fig. 10 is an enlarged elevation of the outer part of the rear side of the machine, the retarding drum being shown in section. Fig. 11 is an enlarged elevation of the outer end of the machine. Fig. 12 is an enlarged plan view of the outer part of the machine. Fig. 13 is a diagrammatic view showing the machine at the beginning of the entering or sumping cut. Fig. 14 is a similar view showing the machine when the sumping cut is partly completed. Fig. 15 is a similar view showing the machine at the end of the sumping cut and ready to start the side cut along the face of the coal. Fig. 16 is a similar view showing the machine during the operation of undercutting along the face of the coal, the manner in which the retarding cable can be passed over the guide sheaves in various ways for moving the machine over the floor of the mine being indicated by the dotted and broken lines. Fig. 17 is a perspective view of the flanged plate which is used to assist in guiding the machine during the sumping cut and to serve as a shoe during the making of the side cut.

The machine comprises a bed frame, a cutter frame projecting from the inner end thereof, propelling and guiding devices mounted on the bed frame, a motor mounted on the bed frame, and suitable driving connections between the motor and the pro-

100

90

95

105

110

pelling devices, the guiding devices, and the cutters, respectively.

Referring to the construction in detail, the bed frame is composed of a bottom plate 1, flanged side plates 2, 2, and a top plate 3, all of which are connected to form a rigid structure. The top plate 3 is preferably in the form of a casting and is formed with front and rear depending brackets 4 and 5, respectively, upon which the cutter frame is mounted. The two parallel sides of the cutter frame are made up of top plates 6, bottom plates 7, and intermediate spacing bars 8 which are secured together as by rivets 9 (see Fig. 3). The space between the outer edges of plates 6 and 7 forms a guide for a cutter chain 10 which may be of any suitable construction. Ways are also formed between the inner edges of the plates 6 and 7, and these ways are adapted to receive flanged projections on the brackets 4 and 5 of the bed frame. The sides of the cutter frame are connected at their front ends by suitable upper and lower plates 11 and 12 between which is mounted a sprocket wheel 13 over which the cutter chain passes. At the outer end of the cutter frame the cutter chain passes over a sprocket wheel 14 which is loosely mounted on an upright shaft 15 carried by the bottom plate 1 of the bed frame. The shaft 15 is preferably connected to the bottom plate by means of a base casting 16 riveted to the bottom plate, the shaft being secured to this base casting by a key 17.

The machine is designed to be propelled along the face of the coal during the cutting operation by a cable or the like, and upon the inner end of the bed frame is mounted a winding drum 18. A suitable draft cable 19 has one end secured to the winding drum so that it can be wound upon the drum when the latter is turned. The cable 19 passes downward from the drum and under a guide sheave or pulley 19^b which is mounted in a block 19^b. This pulley block is in the nature of a caster frame having a hollow cylindrical stem or spindle rotatably mounted in the top plate of the bed frame. The arrangement is such that the cable 19 passes downward through said hollow spindle, and thence under the pulley. With the pulley mounted in this manner, it will be seen that the cable 19 can be taken off in any desired direction within a range of about 180°. The drum 18 is mounted upon a longitudinally disposed shaft 20 carried in bearings 21 and 22. The winding drum 18 is mounted to turn freely on the shaft 20 but is normally turned with the shaft by means of the following connections.

23 is a spur gear which is keyed on the shaft 20 on the outer side of the winding drum, and the latter is clutched to the gear 23 by a plurality of clutch pins 24 which

are slidably mounted in the drum and are adapted to have their ends projected into apertures 25 in the body of the gear 23. The clutch pins 24 are carried and actuated by means of a ring 26 which is slidably mounted on the hub of the drum 18. For convenience of operation the ring 26 is provided with a plurality of handles 26^a which may be grasped by the machine runner to move the clutch pins into or out of operative engagement with the gear 23.

27 is an electric motor which, as to details of construction, may be of any preferred form, and which is mounted upon the outer end of the bed frame with its armature shaft arranged longitudinally of the machine. This motor is designed to drive the winding drum 18 and the cutter chain 10, and to this end the following gearing is provided. The armature shaft 28 of the motor carries at its inner end a bevel pinion 29 which meshes with a bevel gear 30 on the vertical shaft 31. The lower end of this shaft is mounted in a bearing 32 formed in the depending bracket 5 of the bed frame (see Fig. 4). The upper end of the shaft turns in a bearing 33 carried by an upstanding frame or yoke 34 mounted on the bed frame.

35 is a worm which, like the beveled gear 30, is keyed to the shaft 31. This worm meshes with a worm wheel 36, which is mounted upon a longitudinally disposed shaft 37. This shaft is mounted in bearings 38, 39 carried by the top plate of the bed frame. A ball thrust bearing 40 is preferably interposed between the upper side of the bevel gear 30 and the bearing 33 to take the axial thrust of the worm.

The pinion 41 is mounted to turn loosely on shaft 37 adjacent the bearing 39, and upon the front end of the shaft 37 is mounted a spur pinion 42. The latter pinion has a sleeve-like hub extension 42^a which extends through the bearing 38 and has a large spur gear 43 keyed to its rear end. The outer end of the hub of gear 43 is formed with a toothed clutch extension 44 and the pinion 41 also carries on its inner end a toothed clutch element 45. A grooved clutch collar 46 is slidably keyed upon the shaft 37, and by means of it either the pinion 41 or the gear 43 and pinion 42 can, at will, be clutched to the shaft 37. The clutch collar 46 is shifted by means of a lever arm 47 which is secured to the lower end of a vertical shaft 48, said shaft carrying at its upper end a transversely disposed hand lever or bar 49. The lever 49 preferably extends to both sides of the machine so that it can readily be grasped by the operator when standing at either side of the machine. The pinion 41 meshes with a gear wheel 50 which is mounted upon the outer end of a short shaft 51, this shaft being carried by a bearing 52 on the bed frame.

53 is a pinion secured to the inner end of the shaft 51 and meshes with a gear wheel 43. The pinion 42 meshes with a large gear 23 which, as previously stated, is keyed to 5 the shaft 20.

55 is a ball thrust bearing which is interposed between the pinion 41 and the bearing 39 to take any axial thrust that may result from the action of the worm and worm 10 wheel.

It will be seen that by means of the gearing described, the winding drum 18 can be driven at either one of two speeds from the shaft 31, which itself is directly driven by 15 the motor. Thus, if the clutch 46 is thrown so as to make the pinion 41 fast on the shaft 37, the rotation of said shaft will be transmitted through pinion 41 and gear 50 to the shaft 51, thence through pinion 53, gear 20 43, pinion 42 and gear 54 to the winding drum 18. On the other hand, if clutch 46 is thrown so as to connect gear 43 and with it pinion 42 to the shaft 37, the rotation of 25 said shaft is then transmitted directly to pinion 42 and gear 23 to the winding drum 18, thus rotating the latter at considerably 30 higher speed than before. With the clutch thrown as last described, it will be noted that pinion 53, gear 50 and pinion 41 turn idly.

The following devices are provided for driving the cutter chain. On the vertical shaft 31, and near its lower end is mounted a spur pinion 56 which meshes with a large 35 spur gear 57 which is mounted to turn freely upon the upright shaft 15, said gear being disposed directly above the cutter chain sprocket wheel 14. On the upward extending hub 57^a of the gear is slidably 40 mounted a collar 58 which carries a plurality of depending clutch pins 59 which extend through apertures in the web of the spur gear wheel 57. The upper face of the sprocket wheel 14 is provided with a series 45 of hollow semi-cylindrical bosses 14^a, there being one to correspond with each of the clutch pins 59, and when the collar 58 and said pins are in their lowermost position, the pins engage the bosses 14^a so that the rotation of gear wheel 57 is transmitted to 50 sprocket wheel 14. The collar 58 is grooved to receive a band 60 to which is connected a lever arm 61 having its forward end pivotally connected at 62 to the rigid part of 55 the bed frame structure. A link 63 is connected at its lower end to the lever arm 61, and at its upper end is connected to an eccentric band 64 which fits upon an eccentric 60 65. Said eccentric is mounted upon a screw stud 66 which projects from the front face of the frame of motor 27, and the eccentric is provided with a pivoted handle 67, by means of which it can be turned to actuate the link 63 and raise and lower the clutch 65 collar 58. It will be noted that the handle

67 is very conveniently located to be grasped by the operator when he desires to throw the cutter chain into or out of operation.

If it is found desirable the frame metal of the motor 27, which overlies the shaft 15, 70 can be formed with a socket 27^a to receive the upper end of said shaft and give it additional support (see Fig. 5).

I prefer to inclose the inner train of gearing by a casing 68, for obvious reasons. On 75 one side of this casing I mount a rheostat 69 for the motor and an operating shaft 70 extends from the rheostat to the outer end of the bed frame where it is provided with a hand wheel 71 which can be conveniently 80 grasped by the operator when at the outer end of the machine.

My improved devices for guiding the machine or holding it up to its work as it advances along the face of the coal 85 comprise the following parts: On the outer end of the shaft 37 is keyed, or otherwise suitably secured, a pinion 72 which meshes with a gear 73 that is fast on the inner end of a longitudinally extending shaft 74. This 90 shaft is mounted in bearings 75 and 76, the former being bolted to the side of the bed frame and the latter being preferably bolted to the side of the frame of the motor 27.

77 is a cable winding drum rotatably 95 mounted on the outer end of the shaft 74, and interposed between the shaft and the drum is a friction brake or clutch mechanism designated as an entirety by 78. This mechanism, in the construction shown, comprises a pressure plate 79 which is slidably 100 keyed on the shaft 74, friction disks 80 which are formed in the well known manner with notches to engage a rib or ribs on the inner surface of the drum 77, similar friction disks 81 which are notched to engage a rib or ribs on a cylindrical extension 79^a of the pressure plate and arranged alternately with the friction disks 80, a spring 82 interposed between the pressure plate 79 110 and the hub of the drum 77 tending to force the former outward, and an adjusting hand wheel 83 mounted on the threaded end 74^a of the shaft 74 and adapted, when turned, to press the plate 79 inward against the friction disks 80 and 81 which in turn press against the body of the drum 77. By adjusting the hand wheel 83 the friction devices can be controlled to vary the force transmitted from shaft 74 to drum 77 from 120 zero up to a maximum corresponding to the full power with which the shaft is driven.

84 is a retarding cable having one end secured to the drum 77 while its other end is adapted to be secured to any suitable fixed 125 abutment, such as an anchor or a screw jack.

It will be observed that when the motor 27 is driven so as to move the cutter chain in the proper direction for cutting, the shaft 74 is driven in a clockwise direction, as 130

viewed from its outer end, and consequently any rotational movement transmitted from the shaft to the drum 77 tends to wind up the cable 84, the latter leaving the drum from its lower side. Hence, as the machine advances in the undercutting operation, the rotating shaft 74 tends constantly to wind up the cable 84, but slippage in the friction brake or clutch device 79 permits the drum 10 77 to turn in a direction opposite that in which the shaft 74 rotates so that the retarding cable is paid out as the machine advances under a tension which can be varied and controlled at will by means of the hand wheel 83 of the friction mechanism. If it is desirable at any time to swing the outer end of the machine rearward, this can be accomplished by tightening the friction mechanism until the rotation of shaft 74 is 20 transmitted to the drum 77, the consequent winding in of the retarding cable serving to pull the outer end of the machine positively rearward.

In some cases it may be desirable that the 25 friction mechanism 79 be not used as a brake device to control the paying out of the retarding cable, but that it be used only as a clutch device when it is desired to transmit the rotation of the shaft 74 to the winding drum for the purpose of swinging the outer end of the machine rearward during the undercutting operation, and also under other conditions which will presently be referred to. In the construction shown I have 35 therefore provided the drum 77 with a cylindrical flange or extension 77^a and on this is arranged a flexible brake band 85. Clamping lugs 86 and 87 are riveted or otherwise secured to the respective ends of the brake 40 band 85. These lugs are perforated to receive a clamping bolt or screw 88 and the lug 87 is slotted to receive a nut 89. This nut, when the parts are in position as shown, engages the bottom of the slot formed in the 45 lug 87 so that it cannot turn. By turning the bolt 88 one way or the other the brake band may be tightened or loosened as desired. As a convenient means for turning the screw bolt 88, a handle 90 is pivotally 50 secured to the end of said bolt. The lug 86 is formed with a vertical extension or flange 86^a which is perforated so as to pass over a cylindrical boss 76^a formed on an extension 76^b of the bearing bracket 76, and the 55 brake band is thus prevented from being bodily displaced.

It will now be seen that the flexible brake band can be used to control the paying out of the retarding cable 84, and then, if it is 60 desired to swing the outer part of the machine rearward, this can be done by the power of the motor by tightening up the friction devices 79 so as to clutch the drum 77 to the shaft 74, the adjustment of the

brake band 85 remaining undisturbed in the 65 mean time.

As a further means of controlling the winding drum 77 I provide a positive lock which is independent both of the brake band 85 and of the friction devices 79. This lock 70 comprises a pin 91 which is slidably mounted in the bracket extension 76^b in position to engage any one of a series of holes or sockets 92 formed in the adjacent face of the drum 77 or of its extension 77^a. The pin 75 91 is pivotally connected to a hand lever 93 by means of which it can be readily moved into and out of locking position. If this positive lock is thrown into operative position when the machine is advancing, it will 80 be seen that the outer end of the machine is locked against further advance and becomes a fixed or pivotal point about which the machine will swing as the propelling cable is wound in. In a word, the positive 85 lock constitutes a further means by which the angle of the machine to the face of the coal can be changed.

By providing the retarding drum 77 with the above described power connections, I am 90 enabled to use said drum when desired as a power drum for moving the machine over the floor of the mine, for loading it upon the truck, etc. To facilitate such use of the retarding drum I provide guide sheaves suitably mounted on the bed frame over which the retarding cable 84 can be passed and thence led off in various directions so that the tension in the cable can be exerted upon the machine to move it in various directions. 95 One desirable arrangement of guide sheaves is shown in the drawings. At the front side of the drum 77 is a vertically arranged sheave 94 which is adapted to receive the cable 84 as it leaves the drum, and in connection with this sheave 94 I provide three 100 sheaves 95, 96, 97, mounted on the rear outer corner, the middle of the outer end, and the outer front corner, respectively, of the bed frame. I also provide on the rear side of the bed frame a sheave 98. It will be seen that the cable 84 can be led off from the drum 77 under the sheave 94, then around sheave 96 and thence to a fixed abutment, or can be led from the sheave 94 to and around the sheave 97 and thence to the fixed abutment. Again, the cable can be passed from the drum over the sheave 94 and thence around sheave 95 and off to a fixed abutment, or from the sheave 95 can be led to 110 and around the sheave 98 and thence to the fixed abutment. It will be understood, of course, that the tension is thrown off the 115 brake band 85 when the drum 77 is to be used as a power drum for moving the machine. 120

When the machine is brought into a mine room to undercut the coal, the first operation 125

is the making of the entering or sumping cut. During this operation it is necessary to guide the machine as it is advanced longitudinally, and to this end, I provide the following devices.

5 99 is an arm preferably in the form of two cast sections 99^a and 99^b which are secured together by bolts 100. The section 99^a has a depending outwardly turned flange 101, and the section 99^b has a similar flange 102, these flanges being constructed to slidably fit the ways formed between the plates 6 and 7 of the cutter frame. The arm 99 is formed at its outer end with a hook or notch in which 10 is mounted a pulley 103, which is arranged so that the feed cable 19 can be passed over it when said cable is extended inward in making the sumping cut.

15 The operation of the machine will now be readily understood. The machine, on being brought into the mine room, is unloaded from the truck and brought to the face of the coal near the right rib, as shown in Fig. 13. The arm 99 having been moved forward as far as it will go in the cutter frame, the cable 19 is taken inward, passed over the pulley 103 and made fast to an anchor or jack 104 at the face of the coal. A flanged guide plate 105 is then slipped under the 20 machine with its upstanding flange placed against the forward side of the bed frame near the inner end thereof, and is secured in position by a jack 106. The motor having been started, the collar clutch 58 is thrown in, and clutch 46 is thrown into engagement with the pinion 41, thus driving the cutters and turning the winding drum 18 at slow speed. The tension on the cable 19 draws the machine forward against the 25 coal, forcing the cutter frame under the face as the cutters remove the coal. The combined action of the cable tension and reaction on the cutters as the entering cut begins, is to throw the inner end of the cutter frame to the right and the outer end of the machine to the left. This action is counteracted by the engagement of the guide arm 99 with the taut cable, and by the guide plate 105, the former preventing the movement 30 of the cutter frame to the right, while the guide plate prevents the outer end of the machine from swinging to the left. During the first part of the sumping cut, the guide arm 99 moves inward with the cutter frame along the cable 19 until the said arm engages the face of the coal, as shown in Fig. 14. Thereafter the cutter frame 35 slides inward in relation to the guide arm until the sumping cut is finished, with the machine in the position shown in Fig. 15, where, it will be noted, the inner end of the bed frame is forced up to the guide arm. When the machine has thus been advanced 40 fully under the coal, the guide plate 105 is

removed, and the cable 19 is stretched along 65 the face to the left rib where it is made fast to an anchor or jack 107. The rear guide cable 84 is then made fast to an anchor or jack 108 adjacent the right rib, and the machine is again started. At the beginning 70 of the side cut the retarding drum 77 is preferably locked against rotation, this being done either by means of the positive lock 91 or by tightening up the brake band 85. By thus locking the retarding drum, 75 the outer end of the machine is made practically a pivot point, while the cutter bar is swung forward by the winding up of the propelling cable 19. As soon as the machine is swung around to the proper angle for side 80 cutting, the control devices of the drum 77 are arranged or adjusted so as to allow it to pay out the retarding cable 84 under a suitable tension to maintain the machine at the proper angle to the face of the coal as 85 the undercutting proceeds.

Such control of the retarding drum can readily be effected by means of the friction brake 78. By suitably setting this brake, rotation of the drum 77, in a direction to 90 pay out the cable 84, can be opposed by any desired amount of frictional resistance. If the outer end of the machine tends to advance too rapidly in relation to the inner parts of the machine, it is only necessary to 95 tighten the brake by means of the hand wheel 83, and on the other end the brake can readily be loosened if the outer end of the machine is retarded too much.

At times in undercutting it becomes desirable to swing the outer end of the machine rearward quickly without waiting for a gradual change in the angle of the machine as it advances along the face. With my improved construction the quick swinging 105 of the outer end of the machine can be effected with great ease by simply tightening up the brake device 78 until it acts as a clutch causing the drum 77 to turn with the constantly rotating shaft 74. This causes a 110 winding up of the retarding cable 84 and the consequent rearward swinging of the outer end of the machine. The drum 77 can be clutched in this manner to the shaft 74 while the inner winding drum is in operation and the machine advancing, or, if it be desired, the propelling devices can be stopped by throwing the clutch 46 to inoperative position before the clutch 78 is tightened up to swing the outer end of the machine rearward. 115 120

Under some conditions it becomes desirable, while undercutting, to move the machine bodily rearward, and this can readily be effected by means of my improved retarding drum. For example, if the cutters encounter a "roll", sulfur ball or other impenetrable obstruction, it is some times 125

possible, by backing the machine off, to start an upwardly inclined cut that will carry the machine over the obstruction and thence down again to the normal level of the kerf. 5 With my improved machine that can readily be accomplished by passing the retarding cable 84 around guide sheaves 94, 95 and 98 and thence rearward to suitable fixed abutment, whereupon power having been thrown 10 off the propelling drum 18, the clutch 78 can be tightened so as to wind up the cable 84 and draw the machine rearward the desired distance.

While the brake or clutch device 78 can 15 be used in the manner described to control the paying out and retarding cable, it is also possible, as I have previously mentioned, to effect the control of the paying out of the cable by means of the band brake 20 85, using the clutch 78 only when it is desired to apply power to the drum 77 to wind in the cable either for the purpose of swinging the machine or moving it bodily in the various manners which have been described.

25 When the undercutting has been completed, the retarding drum and cable can be used to drag the machine from the kerf, across the room, and to load it upon the truck upon which it is transported in the mine. To do this the retarding cable 84 may be passed under the guide sheave 94, then around the sheave 96 and thence to the jack or other fixed abutment toward which the machine is to be drawn. Then 30 by tightening the clutch 78, power is applied and the movement of the machine readily effected. During such handling of the machine the power can of course be thrown off the winding drum 18 and also 35 the cutters can be disconnected from the motor by simply throwing the clutch handle 67. Usually it is desirable to keep the cutter chain running until the cutters have been drawn out of the kerf. When the machine 40 has been drawn over to the truck, it can be loaded on the truck with great ease by means of the power driven drum 77. The cable 84 having been attached in the usual manner to the frame of the truck, the operator 45 is enabled to apply the power to draw the machine endwise onto the truck by simply manipulating the hand wheel 83. The machine can be loaded in this manner with very great ease and convenience be- 50 cause the machine runner is enabled to stand at the outer end of the machine in a position where he can see whether the machine is moving properly onto the truck, and for the further reason that the runner can control 55 the speed of the winding drum with considerable nicety by simply adjusting the hand wheel 83.

In the handling of the machine it may of course be desirable in some cases to use for

this purpose the drum 18 and the cable 19, 65 as when it is desired to unload the machine from the truck, and in other cases in which convenience might dictate the use of the inner drum and cable rather than the outer drum 77 and cable 84. In this connection it 70 will be observed that the various guide sheaves mounted on the bed frame are adapted for use in connection with the cable 19.

What I claim is:—

1. In a mining machine, the combination 75 of a bed frame, power driven cutting apparatus projecting from the inner end of the bed frame, a power actuated cable arranged to exert a forward draft on the inner part of the bed frame to propel the machine along the face of the coal, a winding drum on the bed frame, a retarding cable having one of its ends attached to the winding drum and being adapted and arranged to extend rearward from the machine to an anchor and exert a retarding draft on the outer part of the bed frame, and power actuated driving devices for the said drum rotating in a direction to wind up the retarding cable, said driving devices 80 comprising an adjustable friction transmission clutch adapted either to transmit the rotation of the driving devices so as to cause rotation of the drum in the direction to wind up the retarding cable or to permit rotation of said drum in the opposite direction with various degrees of frictional resistance as the machine is advanced along the face of the coal in the cutting operation. 85

2. In a mining machine, the combination 90 of a bed frame, cutting apparatus projecting from the inner end of the bed frame, a winding drum mounted on the bed frame, a feed cable having one end secured to said winding drum and adapted to exert a forward draft on the inner part of the bed frame to propel the machine along the face of the coal, a second winding drum mounted on the bed frame, a retarding cable having one of its ends attached to the last 95 named winding drum and being adapted and arranged to extend rearward from the machine to an anchor or the like and exert a retarding draft on the outer part of the bed frame, a motor on the bed frame, driving connections between the motor and the cutting apparatus, driving connections between the motor and the first named winding drum, and driving connections between the motor and the retarding cable drum rotating in a direction to wind up the retarding cable, said devices comprising an adjustable friction transmission clutch adapted either to transmit the rotation of the driving devices 100 so as to cause rotation of the drum in the direction to wind up the retarding cable or to permit rotation of the drum in the opposite direction with various degrees of frictional resistance as the machine is advanced along the face of the coal in the cutting operation. 105

tional resistance as the machine is advanced along the face of the coal in the cutting operation.

3. In a mining machine, the combination of a bed frame, cutting apparatus projecting from the inner end of the bed frame, a cable arranged to exert a forward draft on the inner part of the bed frame to propel the machine along the face of the coal, a winding drum to which one end of the said cable is connected, a retarding cable arranged to exert a rearward draft on the outer part of the bed frame, a winding drum on the bed frame to which one end of the retarding cable is connected, a motor on the bed frame, driving connections between the motor and the cutting apparatus, driving connections comprising a disengageable clutch between the motor and the first named winding drum, and driving connections between the motor and the retarding cable drum rotating in a direction to wind up the retarding cable, said devices comprising an adjustable friction transmission clutch adapted either to transmit the rotation of the driving devices so as to cause rotation of the drum in the direction to wind up the retarding cable or to permit rotation of the said drum in the opposite direction with various degrees of frictional resistance as the machine is advanced along the face of the coal in the cutting operation.

4. In a mining machine, the combination of a bed frame, cutting apparatus projecting from the inner end of the bed frame, a power actuated cable arranged to exert a forward draft on the inner part of the bed frame to propel the machine along the face of the coal, a winding drum on the bed frame, a retarding cable having one of its ends attached to the winding drum and being adapted and arranged to extend rearward from the machine to an anchor or the like and exert a retarding draft on the outer part of the bed frame, and power actuated driving devices for the said winding drum rotating in a direction to wind up the retarding cable, said devices comprising adjustable yieldable friction parts adapted when tightened to cause rotation of the drum in the direction to wind up the retarding cable and when loosened to permit rotation of the drum in the opposite direction with various degrees of frictional resistance.

5. In a mining machine of the class described, the combination of the bed frame, the cutting apparatus carried thereby, means for moving the frame and cutting apparatus bodily, laterally, along the coal during operation, yielding means for adjustably retarding the advance of the frame, and power actuated devices independent of the feeding devices for causing the retarding devices to

bodily move the frame backward while the cutting apparatus is in action.

6. In a mining machine of the class described, the combination with the bed frame, the cutting apparatus carried thereby, said frame and cutting apparatus adapted to be moved bodily, laterally, along the coal during operation, the retarding cable, the winding drum therefor, and the adjustable yielding devices for resisting the rotation of the drum when the cable is unwinding, of the power actuated devices adapted to rotate the drum in the cable-winding direction while the cutter is bodily advancing, and optionally controllable means for causing said power devices to rotate the drum in said direction.

7. In a mining machine, the combination of a bed frame, cutting apparatus projecting from the inner end of the bed frame, a winding drum mounted on the bed frame, a feed cable having one end secured to said winding drum and adapted to exert a forward draft on the inner part of the bed frame to propel the machine along the face of the coal, a second winding drum mounted on the bed frame, a retarding cable having one of its ends attached to the last named winding drum and being adapted and arranged to extend rearward from the machine to an anchor or the like and exert a retarding draft on the outer part of the bed frame, a motor on the bed frame, driving connections between the motor and the cutting apparatus, driving connections comprising a disengageable clutch between the motor and the first named winding drum, and driving connections between the motor and the retarding cable drum rotating in a direction to wind up the retarding cable, said devices comprising adjustable yieldable friction parts adapted when tightened to cause rotation of the drum in the direction to wind up the retarding cable and when loosened to permit rotation of the drum in the opposite direction with various degrees of frictional resistance, the feed cable and its winding drum being actuated independently of the retarding cable drum.

8. In a mining machine, the combination of a bed frame, cutting apparatus projecting from the inner end of the bed frame, a power actuated cable arranged to exert a forward draft on the inner part of the bed frame to propel the machine along the face of the coal, a retarding cable arranged to exert a rearward draft on the outer part of the bed frame, a winding drum on the bed frame to which one end of the retarding cable is attached, power actuated driving devices for the said drum which are disconectible independently of the said draft cable and arranged to rotate in a direction to wind up the retarding cable, and friction

devices adapted to resist the rotation of the drum in the opposite direction when the said driving devices are not in effective operation.

- 5 9. In a mining machine, the combination of a bed frame, cutting apparatus projecting from the inner end of the bed frame, a winding drum mounted on the bed frame, a feed cable having one end connected to the 10 winding drum and arranged to exert a forward draft on the inner part of the bed frame to propel the machine along the face of the coal, a second winding drum mounted on the bed frame, a retarding cable having one end secured to the winding drum and being adapted to extend rearward from the machine to an anchor or the like and exert a 15 retarding draft on the outer part of the bed

frame, a motor on the bed frame, gearing between the motor and the first named winding drum adapted to drive said drum at a relatively slow speed, and gearing between the motor and the retarding cable drum adapted to drive the latter at a relatively fast speed, the last named gearing comprising 20 a manually operable friction clutch by which the rotation of the retarding drum can be controlled independently of the action of the feed cable and its drum.

In testimony whereof, I affix my signature, in presence of two witnesses.
